John F. McNamee

Inventor.

Michael Moore

Michael Moore, of Brooklyn, N.Y.

DES. 2004

Letter Patent No. 244, Dated Dec. 16, 1866.

Design for a Table Caster.

The schedule referred to in these letters is tent and making part of the same.

I call your attention to the same.

Be it known that Michael Moore, of Brooklyn, in the County of Kings and State of New York, have invented and do now desire to have a Design for a Table Caster; and I do hereby declare that the following is a full, clear and exact description thereof, which will enable others skilled in the art to make and use the same, referring being had to the accompanying drawing forming part of this specification.

The drawing represents an elevation of a table caster showing my design.

This design consists in inserting in the base of the caster and also in the revolving cructor bottle holder of the same a series of colored glass balls or spheres to serve as an ornamentation or embellishment for the caster.

A represents the base of the caster. B the upright stem and C the revolving cructor bottle holder.

The configuration of these parts constitutes no part of my design.

On the base A of the caster there are inserted a series of small glass balls or spheres D, of the same or of different colors as plainly shown in the drawing, and similar glass balls or spheres E are inserted in the crutor of the revolving cructor bottle holder C, which are also plainly shown in the drawing.

DES. 2004

2
These glass balls or spheres give a neat and dainty appearance to the vase, forming a pleasing contrast with the white metal or silver exterior of the same.

I claim as new and desire to secure by letters patent

A table vase provided with colored glass balls or spheres to form a new and original design, embellishment or ornamentation for the same, substantially as hereinafter described.
